PAPER DISPENSER

Marshall H. Muse, New York, N. Y.

Application March 4, 1938, Serial No. 193,819

1 Claim.

(Cl. 93—1)

This invention relates to paper dispensers and particularly to apparatus of this character for dispensing a measured length of paper.

In cylinder printing presses the pad of the bed roll is provided with an outer cover of oiled paper or the like. In applying the oiled paper to the bed roll the free end thereof is inserted in an opening or slot provided between the semi-cylindrical bed roll sections which may be moved away from each other to receive the end of the paper and then brought together so as to clamp the end of the paper in position. The oiled cover paper is quite expensive and heretofore there have been no means for accurately dispensing the desired length of paper and for turning down the desired size flap or margin which is inserted in the slot in the bed roll. It will be appreciated that in rolls of different lengths a different size strip of paper must be dispensed. It will also be appreciated that the flap or margin must be accurately measured and must be formed at right angles to the lateral edges of the pages. Heretofore a length of paper was dispensed and then it was trimmed to the desired size, with the result that there was considerable waste of paper. Also the accurate measurement and folding of the flap resulted in wasting a considerable amount of time.

It is an object of this invention to overcome the difficulties heretofore encountered and to provide an improved paper dispenser particularly suited for dispensing a predetermined measured length of paper and for providing the strip of paper with a marginal crease spaced a predetermined distance from one edge of the strip and disposed at right angles to two of the edges thereof.

A further object is the provision of an improved paper dispenser of the above character in which the measured amount of paper that is dispensed thereby and also the spacing of the crease from the edge of the strip may be readily varied so as to adapt the dispensed paper to bed rolls of various sizes.

For a fuller understanding of the invention reference should be had to the accompanying drawings, in which

Figure 1 is a side view of a paper dispenser embodying my invention;

Fig. 2 is a sectional view in the direction of the arrows on the line 2—2 of Fig. 4;

Fig. 3 is a sectional view in the direction of the arrows on the line 3—3 of Figure 1;

Fig. 4 is a front elevation of the dispensing apparatus with the central portion omitted;

Fig. 5 is a detail view showing the creasing roller and one end of the feed rolls;

Fig. 6 is a perspective view of the end of the dispensed paper showing the manner in which the marginal flap is turned down; and

Fig. 7 is a perspective view showing the dispensed paper formed into a cylinder in the manner that it is applied to the bed roll of the cylinder printing press.

My paper dispenser consists primarily of a pair 10 of feed rolls 10 and 11 mounted on shafts 12 and 13 which are suitably journaled in the brackets or uprights 14 and adapted to feed or dispense paper from the supply roll 15 mounted upon the shaft 16 which is supported adjacent its two ends in slots 17 formed in the brackets 14 beneath the feed rolls 10 and 11. The feed rolls 10 and 11 are preferably provided with a peripheral coating indicated at 18, formed of some suitable yielding resilient material such as rubber, so as to increase the frictional engagement and to insure positive feeding of the paper. The rollers are disposed in relatively tight engagement so that rotation of one will cause rotation of the other and likewise will cause feeding of a strip of paper projected between the rolls. I provide suitable means for rotating the rolls, preferably in the form of a crank or handle 19 secured to the end of the shaft 12 of the lower roll on the outside of one of the brackets 14.

It will be seen that due to the fact that shaft 16 on supply roll 15 is mounted in the end of slot 17 the supply roll can be readily and conveniently inserted in the brackets and removed therefrom. A roll of the desired type of paper should be inserted as shown and the end of the paper fed upwardly between the feed rolls 10 and 11. As stated, my paper dispenser is particularly suited for dispensing heavy oiled paper or the like to be used as a protective coating on the bed roll 40 of a cylinder printing press, and accordingly a roll of paper of this character is preferably inserted in the device.

So as to provide for a depending flap or margin of the desired predetermined width my apparatus 45 preferably includes a creasing disk or roller, indicated at 20, mounted on shaft 21, which in turn is carried by the arm or bracket 22. The creasing disk or roller 20 engages feed roll 10 at a point in the paper feed prior to roll 11. The 50 periphery of the creasing disk or roller is preferably tapered as shown most clearly in Fig. 5 and it presses against feed 10 so as to impart a crease in the paper being fed therebetween as shown most clearly at 23 in Fig. 4.

40

55

For different bed rolls it is desirable to have margins or flaps of varying width and for this reason I provide the creasing disk or roller with an adjustable mounting in the form of a collar 5 formed at the end of the bracket 22 and disposed around the horizontal adjusting shaft 24 which is preferably provided with graduations 25 as shown, so as to indicate the spacing of the crease from the edge of the paper. It will be appreciated 10 that the creasing disk or roller may be adjusted along shaft 24 so as to provide a marginal flap of the desired width, and in order to retain the creasing disk or roller in the desired adjusted position I preferably provide a set screw 26 in the bracket 22, which is adapted to engage the 15 shaft 24.

I also provide my improved paper dispenser with suitable means for indicating and limiting the length of the strip of paper dispensed 20 thereby. This means preferably takes the form of a geared disk 27 of relatively large diameter mounted upon stub shaft 28 which is engaged and operated by the relatively small pinion 29 carried by shaft 12 of roller 10 adjacent the 25 handle 19. Formed around the disk at regularly spaced intervals adjacent the periphery thereof are a series of apertures 30 adapted to receive a removable pin 31 which engages the stop 32 when it reaches the top of its path of rotation so as 30 to limit the operation of the paper feed when the disk 27 has been rotated a predetermined distance. It will be seen that the stop 32 is secured to the bracket 14 beneath the disk 27 and in registry with the openings 30 when they are 35 positioned adjacent the top of the disk, and is accordingly in the path of movement of the pin 31 when it is protruded through one of the openings 30. The distance between apertures 30 is uniform with the result that rotation of handle 40 19 a sufficient distance to cause rotation of disk 27 for the distance between two adjacent apertures will result in the dispensing of a uniform predetermined length of paper. When the handle 19 is turned in a clockwise direction as viewed in 45 Fig. 1 it will cause the paper to feed outwardly from the feed rollers and will also cause the disk 27 to rotate in a counter-clockwise direction in the direction of the arrow in Fig. 1. Before turning the crank 19 the pin 31 is placed in one of the apertures 30 the desired distance from 50 stop 32 so that the handle 19 may be rotated to dispense the desired length of paper. The handle 19 is then turned until the pin 31 engages stop 32. The operator will then know that the 55 desired amount of paper has been dispensed.

So as to facilitate severing the dispensed predetermined length of paper from the strip of paper I preferably provide a cutting device 33 in the form of an inverted U-shaped channel member 60 34 serving as a platen and an inverted U-shaped channel member 35 spaced from and positioned above the platen 34 as shown. The strip of paper is threaded between the members 35 and 34 and it will be observed that when the paper is dispensed by the rollers it will be fed 65 through the cutting device as shown.

In using my device the creasing disk or roll is adjusted along shaft 35 to provide a margin or flap of the desired width. The supply roll 15 of the desired type of paper is then placed in the brackets 14 and the paper strip is fed upwardly between the creasing roll 20 and feed roll 10, between the feed rolls 10 and 11 and thence through the cutting devices 33. The lead-

ing edge of the strip of paper is then severed at the cutting device by tearing the paper along the straight edge at the forward end of the device. Pin 31 is then placed in the aperture 30 which will provide for dispensing of the desired 5 predetermined length of paper. Crank 19 is then rotated in a clockwise direction as viewed in Fig. 1 with the result that the paper is fed between the rolls and thence outwardly through the cutting device. When the pin 31 engages the stop 10 32 it will be appreciated that the desired predetermined length of paper has been dispensed. The paper is then severed by tearing it along the straight edge of the cutting device. The dispensed length of paper which is indicated by 15 the numeral 37 is then folded along the crease line 23 to produce the marginal flap 38. The flap is then inserted in the slot or opening in the bed roll of the cylinder printing press, and the paper rolled transversely of the strip around the 20 roll as shown in Fig. 7. To dispense an additional length of paper the pin 31 is again placed the proper distance from stop 32 and the handle 19 is turned until the pin engages the stop. Where the paper is to be used with bed rolls of 25 different axial lengths the spacing of pin 31 from stop 32 is varied accordingly. The width of the margin or flap 38 may also be varied to suit the particular bed roll.

To facilitate adjustment of the paper feed so 30 as to feed the desired predetermined length of paper the bracket 14 may be calibrated around the periphery of disk 27 so as to indicate the length of paper that will be fed if the pin is inserted in the aperture 30 positioned nearest the 35 calibration or marking.

From the foregoing it will be appreciated that I have provided an improved paper dispenser particularly suited for dispensing paper to be used as a protective cover for a bed roll of a 40 cylinder printing press and which may be adjusted to dispense any desired predetermined length of paper and to form a crease at the desired predetermined distance from one of the edges of the paper. 45

It should be understood that modifications may be made in the illustrated and described embodiment of my invention without departing from the invention as set forth in the accompanying claim. 50

I claim:

A paper dispenser of the type described comprising a frame having means for supporting a paper supply roll, a pair of feed rollers mounted on the frame and adapted to feed the paper from the supply roll, means for rotating the feed rolls, a shaft mounted on the frame and parallel to the axis of the feed rolls, a creasing roller adjustably mounted on the shaft in engagement with one of the feed rolls so as to impress a crease in the paper, and means for limiting the rotation of the feed rolls so as to provide for the feeding of a predetermined length of paper, said last-named means comprising a member mounted on the frame and operatively connected to the feed-rolls so as to rotate therewith and provided with a plurality of uniformly spaced apertures arranged in a circle concentric with the mounting, a stop mounted on the frame and a removable pin co-operable to be inserted in any one of the apertures and to engage the stop after the member and rolls have rotated a predetermined distance so as to limit the rotation thereof. 70
